Attorney.

UNITED STATES PATENT OFFICE.

GERALD R. LIVERGOOD, OF ST. JOSEPH, MISSOURI.

TROLLEY CIRCUIT-FORMER.

No. 852,969.

Specification of Letters Patent.

Patented May 7, 1907.

Application filed January 29, 1906. Serial No. 298,508.

To all whom it may concern:

Be it known that I, GERALD R. LIVERGOOD, a citizen of the United States, residing at St. Joseph, in the county of Buchanan and State of Missouri, have invented certain new and useful Improvements in Trolley Circuit-Formers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

The object of my invention is to provide a mechanism to be used on trolley systems that will automatically close and open at fixed places a local circuit on the car in connection with a street or station indicator, and provide for back ups and to recover from same without closing circuit a second time on second contact with same switch terminals.

I accomplish my object by the mechanism illustrated in the accompanying drawings, in which,

Figure 1 is a detail cross sectional top view of a terminal for a trolley pole showing a frame with clamp for holding the same in position, a double finger wiper cam, a shaft, a twist spring in position and a tube containing a thrust spring and plunger; Fig. 2 is an end view of a terminal for a trolley hanger; Fig. 3 is a side view of a terminal for a trolley hanger, and Fig. 4 is a side view of the complete mechanism of the device showing a terminal clamped to a trolley pole about to pass and contact with another terminal clamped into position on a trolley hanger.

The device consists of a containing frame A designed to fit the contour of trolley pole O and to be clamped thereto by clamps L L hinged to said frame at M M. The other end of said clamps to be fastened to said frame by screw bolts N N, said frame and clamps to be insulated from said pole.

B is a double wiper cam consisting of two fingers Y and Z at right angles pivotally attached to frame A by shaft C having its terminals in bearings in said frame. D is a twist spring about shaft C having one end fastened to the frame at E, the other end fastened to cam B at F.

G is a tube closed at its outer end and fastened rigidly to frame A. H is a plunger working in said tube. K is a slot in side of

said plunger J—a pin passing through said slot and having its terminals fastened rigidly in tube G.

I is a thrust spring fitting inside tube G and keeping plunger H, normally, at its full-est extension. The plunger may travel back and forth in said tube the length of the slot in said plunger.

X is a terminal designed to fit between U and W of a trolley hanger and is provided with a hole X' (Fig. 2) in top of said terminal.

S are legs provided with notches T T adapted to engage and be held in position by part U of the trolley hanger.

R is a contact point of terminal X.

P and Q are cam faces at right angles on cam B.

Finger Y and face Z' of finger Z are cov- 75 ered with insulating material.

A' is a wire attached to frame A and forming connection to the local circuit in the car and thence to ground connections.

Ordinarily the circuit remains open but 80 when the trolley passes the terminal on the hanger the cam B with finger Z wipes and forms contact with point R of terminal X. In doing so cam B turns backward on shaft C, the spring D recovering said cam to its 85 normal position after the trolley passes terminal X. Should the trolley be backed past terminal X the point R would contact with insulated face Z' of finger Z and the entire cam B would move and be thrown forward a 90 quarter turn from its normal position by the action of thrust spring I on plunger H, said plunger pushing against face P of cam B. The cam B would then remain in its new position until the trolley moved forward again 95 when point R would contact with insulated finger Y and return cam B to its normal position.

What I claim and desire to secure by Letters Patent, is,

1. In a trolley circuit former the combination of a containing frame, clamps to hold same in position, a wire attached to containing block and adapted to be connected with a local circuit on a car, a cam having duplicate 105 wiper fingers at right angles one of said fingers insulated on its back face, the other entirely insulated, a shaft adapted to pivotally attach said cam to the containing frame, a twist spring about said shaft one end of which 110 is fastened to said cam, the other end fastened to the containing frame, a tube closed at its

outer end fastened rigidly to said frame, a plunger, provided with a slot in one side, adapted to fit in said tube, a pin adapted to pass through said slot in the plunger and to have its ends fastened rigidly in said tube, a thrust spring adapted to fit in said tube and to normally hold said plunger to its fullest extension, cam faces at right angles on said cam to be acted on by said plunger, a terminal provided, with a hole in top, duplicate legs provided with notches and a contact point, said terminal being adapted to be engaged by and clamped into position between the separate parts of a trolley hanger.

2. In a trolley circuit former the combination of a containing frame, clamps to hold the same in position, a wire attached to containing block and adapted to be connected with a local circuit on a car, a cam having duplicate wiper fingers at right angles one of said fingers insulated on its back face, the other entirely insulated, a shaft adapted to pivotally attach said cam to the containing frame, a twist spring about said shaft, one

end of which is fastened to said cam, the other end fastened to the containing frame, a tube closed at its outer end, fastened rigidly to said frame, a plunger provided with a slot in one side, adapted to fit in said tube, a pin adapted to pass through said slot in said plunger its ends fastened rigidly in said tube, a thrust spring adapted to fit in said tube and to normally hold said plunger to its fullest extension and the cam faces at right angles on said cam to be acted on by said plunger.

3. In a trolley circuit former, a terminal provided with a hole in its top, duplicate legs provided with notches and a contact point, said terminal being adapted to be engaged by and clamped into position between the separate parts of a trolley hanger.

In testimony whereof, I affix my signature, in presence of two witnesses.

GERALD R. LIVERGOOD.
